UNITED STATES PATENT OFFICE.

MORRIS E. CONN, OF PHILADELPHIA, PENNSYLVANIA, ASSIGNOR TO THE ACME STAPLE COMPANY, LIMITED, OF SAME PLACE.

DESIGN FOR A MALE MEMBER FOR DEVICES FOR LOCKING FORMS OF TYPE, &c., IN CHASES AND FRAMES.

SPECIFICATION forming part of Design No. 31,261, dated July 18, 1899.

Application filed June 12, 1899. Serial No. 720,305. Term of patent 14 years.

To all whom it may concern:

Be it known that I, MORRIS E. CONN, a citizen of the United States, residing in the city of Philadelphia, State of Pennsylvania, have invented and produced a certain new and original Design for the Male Member of a Printer's Device for Locking a Form of Type in a Chase, of which the following is a full, clear, and exact description, reference being had to the accompanying drawings, forming a part of this specification.

My invention relates to a novel design in form or configuration of the male member of a device used by printers for locking a "form" of type in chases and frames and is comprised within the technical term "furniture;" and my new design for such device is shown in the accompanying drawings, in which—

The design consists of the straight-faced end portion A, having a projecting arm C at right angles thereto, said projecting arm being provided on each of its sides for a part of its length with serrated ribs or flanges d d, adapted to be employed with an opposite member described in an application for patent, Serial No. 707,224, filed by me February 26, 1899.

Having thus described my invention, what I claim as new is—

The design for the male member of a device for securing a "form" of type &c. in chases and frames, substantially as described.

In testimony whereof I have hereunto affixed my signature this 8th day of June, A. D. 1899.

MORRIS E. CONN.
